Primary Examiner — Andrew Kerr*Assistant Examiner* — Chariton Alexakis(74) *Attorney, Agent, or Firm* — Walter J. Tencza, Jr.(57) **CLAIM**

We claim the ornamental design for the grinder apparatus, as shown and described.

DESCRIPTION

FIG. 1 is a front, top perspective view of a grinder apparatus, showing my design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a front and top perspective view thereof in a disassembled state; and,

FIG. 9 is a top plan view thereof.

The broken lines showing in the drawings depict portions of the grinder apparatus that form no part of the claimed design.

1 Claim, 8 Drawing Sheets(56)
